UNITED STATES PATENT OFFICE.

HENRY CÔTÉ, OF WEST WARREN, MASSACHUSETTS, ASSIGNOR TO WARE MACHINE & LOOM COMPANY, OF WARE, MASSACHUSETTS, A CORPORATION OF MASSACHUSETTS.

PICKER-STICK CHECK.

1,023,362.

Specification of Letters Patent.

Patented Apr. 16, 1912.

Application filed April 8, 1911. Serial No. 619,652.

To all whom it may concern:

Be it known that I, HENRY CÔTÉ, a citizen of the United States, residing at West Warren, county of Worcester, State of Massachusetts, have invented an Improvement in Picker-Stick Checks, of which the following description, in connection with the accompanying drawing, is a specification, like characters on the drawing representing like

10 parts.

This invention relates to picker stick checks which are adapted to check the inward movement of the picker stick so as to prevent it from striking against the end of 15 the slot in the lay, and the object of the invention is to provide a simple check of this nature which can be readily applied to any picker stick which operates in conjunction with a rocker foot.

20 Some embodiments of the invention will first be described and then the novel features thereof will be pointed out in the appended claims.

25 In the drawings Figure 1 is a view of the rocker, rocker foot and picker stick of a loom showing my improvements applied thereto; Fig. 2 is a similar view showing a slightly different construction from that shown in Fig. 1; Fig. 3 is an end view of the 30 device shown in Fig. 1; Fig. 4 is a section on the line $x-x$, Fig. 1; Fig. 5 is a view similar to Fig. 3 but showing an arrangement having two checking springs; Fig. 6 is a perspective view of one of the parts of my 35 device.

3 designates a portion of the loom frame, 4 the rock-shaft carrying the rocker foot 5, and 6 is the picker stick which has the rocker 7 secured to the lower end thereof by 40 the bolt 8 in usual manner. These parts are such as are commonly found in looms employing a picker stick with the rocker foot construction and form no part of the present invention and may, therefore, be of any suitable or usual construction. In applying my 45 invention to this rocker foot construction I secure a spring or other cushion device to the rocker foot and provide an arm extending laterally from the picker stick with 50 which said spring has engagement, so that when the picker stick is moved forward to throw the shuttle across the lay the spring will be put under tension and will act as a cushion device to cushion the inward movement of the picker stick and prevent the lat-

ter from striking against the end of the slot in the lay. The laterally-extending arm with which the spring has engagement is shown at 9 and it may be secured to the picker stick in a variety of ways without departing from my invention. As herein shown it is made as an integral part of a plate 10 which is secured to the picker stick and which is herein shown as having the shape illustrated in Fig. 6, that is, it is provided with the stem portion 11 which overlies the picker stick and is clamped between the latter and the portion 12 of the rocker foot and is also formed with the downwardly-extending portion 13 which is situated at one side of the picker stick and at the lower end of which the laterally-extending arm 9 is situated. This member 10 can be conveniently formed from a piece of sheet metal bent into the shape illustrated in 75 Fig. 6.

The spring or cushion device is designated 14 and it is illustrated as sustained by a pin or post 15 which is secured to the rocker foot 5 and extends up through the laterally-extending arm 9 and is provided at its upper end with a collar or nut 26. The spring 14 is shown as encircling this post or pin 15 and as confined between the arm 9 and the collar 26. The post or pin may be secured to 80 the rocker foot 5 in any suitable way. If the device is to be applied to a rocker foot which is equipped with the usual heel strap spring and which is, therefore, provided with the laterally and downwardly-extending 85 bracket 16 for supporting said spring, I propose to secure said pin 14 to a holder or supporting member 17 which is shaped to be sustained by said bracket 16. The holder shown in Fig. 1 comprises the horizontally-extending body portion which lies alongside of the rocker foot 5 and extends over the top of the bracket 16 and is provided with the downwardly-extending arm 18 which passes in back of the bracket 16 and has an eye or loop 19 at its lower end through which a clamping bolt 20 passes, said bolt serving to clamp the arm 18 to the bracket 16. The horizontal body portion 17 is also 90 clamped to the bracket by means of a clamping bolt 21 which extends down through said support and is provided with a head 22 which engages underneath the bracket 16. The pin or post 15 is secured to this support or holder 17 in any suitable way as by 100 105 110

ing the end thereof inserted therethrough and by being held in position by the clamping nuts 23. With this construction it will be readily observed that when the picker stick is moved forwardly into the dotted line position in Fig. 1 thereby to throw the shuttle across the lay, the rocking movement of the rocker 7 will through the arm 9 operate to compress the spring 14 and the 10 spring will, therefore, act as a check to the movement of the picker stick. As soon as the picking motion ceases its operation, the spring 14 which is under compression will throw the rocker foot backwardly and thus 15 return the picker stick to its initial position ready for the next pick. The spring 14, therefore, not only serves to check the forward motion of the picker stick and prevent the latter from striking against the end 20 of the slot in the shuttle box, but also acts to return the picker stick to its normal position. The tension of the spring 14 can be readily adjusted by means of the adjustable collar 26, as will be readily understood. 25 In Fig. 2 I have shown a slightly different construction wherein the post or pin 15 is secured directly to a lug or ear 170 formed integral with the rocker foot 5, but in other respects the invention is exactly like that 30 shown in Fig. 1. Fig. 2 shows the way in which my invention might be embodied in a loom if an entirely new rocker foot was to be employed, while Fig. 1 shows the way in which the invention might be embodied in 35 a loom without discarding the old rocker foot.

In Fig. 5 I have illustrated an embodiment of the invention wherein two checking springs 14 are employed, one on each 40 side of the picker stick. In this construction I will employ a plate 10 which has two portions 13, one on each side of the picker stick, each of which is provided with a laterally-extending arm 9 and the rocker foot 45 will be provided with the two lugs 170, one on each side thereof, each of which carries a post or pin 15, each pin sustaining a checking spring or cushion device 14.

It will be noted that my invention is 50 comparatively simple and can be readily applied to any loom. When the construction shown in Fig. 1 is employed the supporting member 17 may be made more or less resilient if desired so that part of the checking action will be due to the resiliency of 55 said support or said member may be entirely rigid if preferred.

Having fully described my invention,

what I claim as new and desire to secure by Letters Patent is:—

60

1. In a picker stick check, the combination with a rocker foot, of a rocker thereon, a picker stick secured to the rocker, a U-shaped plate, one arm of which is clamped between the rocker and picker stick and the other arm of which extends downwardly at the side of the picker stick and the end of which is bent laterally and slotted, a vertically-disposed pin secured to the rocker foot and extending upwardly through said slot, and a spring sustained by said pin and bearing against the upper side of said arm.

65

2. In a picker stick check, the combination with a rocker foot, of a rocker thereon, a picker stick secured to the rocker, a plate 75 provided with a stem which is clamped between the picker stick and the rocker foot, and also provided with a downwardly-extending arm, the end of which extends laterally and is situated at the side of the 80 picker stick, and a spring acting on said laterally-extending portion and serving to check the forward movement of the picker stick.

70

3. In a picker stick check, the combination with a rocker foot having a laterally and downwardly-extending lug, of a rocker thereon, a picker stick secured to the rocker, a laterally-extending arm associated with the picker stick, a plate secured to the laterally and downwardly-extending lug, a pin carried by said plate and extending above 90 said arm and having a collar thereon, and a spring carried by the pin and acting at one end against said collar and at the other on the arm to cushion the forward movement of the picker stick.

85

4. In a picker check, the combination with a rocker foot, of a rocker thereon, a picker stick secured to the rocker, a plate clamped 100 between the picker stick and rocker and provided with a horizontally-arranged slotted portion situated at one side of the picker stick, a pin fixedly secured to the rocker foot and extending vertically through said 105 slot, a collar on the pin, and a spring interposed between the collar and the slotted portion of the plate.

90

In testimony whereof, I have signed my name to this specification, in the presence of 110 two subscribing witnesses.

HENRY CÔTÉ.
